UNITED STATES PATENT OFFICE

JOSEPH H. DILLON, OF WILMETTE, ILLINOIS, ASSIGNOR TO DILLON PULLEY CO., OF CHICAGO, ILLINOIS, A CORPORATION OF ILLINOIS

PULLEY

Application filed January 5, 1922, Serial No. 527,190. Renewed January 30, 1929.

My invention relates to builder's hardware, and more specifically to an improved pulley and support therefor, constituting an article of manufacture commonly referred to as an 5 entirety as a sash pulley.

One primary object of the invention is to improve the functioning of devices of this sort.

A more specific object is to provide guiding baffles and apertures of a better and more 10 efficient shape than have heretofore been constructed.

Another primary object is to diminish the cost of the finished article without decreasing 15 either its strength or durability.

A more specific object is to provide for the use of lighter metal by embossing the sides 20 of the casing to strengthen it.

Another object is to diminish the number 25 of parts, more particularly by forming the entire casing of a single piece.

Another object is to simplify the shape of the parts and simultaneously provide a more positive fastening engagement between the 30 parts.

Further objects and advantages of the invention will become apparent as the description proceeds.

In the accompanying drawings, 35 Figure 1 is a plan view of a blank from which the casing is to be formed;

Fig. 2 is a sectional view of the finished article; and

Fig. 3 is a section on line 3—3 of Fig. 2.

The disclosure herein is in the nature of 35 an improvement on Patent 1,224,152 to Joseph J. Dillon, May 1, 1917, and on my co-pending application, Serial No. 537,398 filed February 18, 1922.

In the embodiment of my invention selected 40 for illustration the entire support for the pintle 10, and casing for the pulley 12 comprises only two pieces of metal; a blank 14 and a face plate 16.

The blank 14 is de- 45 formed by suitable dies into the shape indicated in Fig. 2, the portion indicated in Figure 1 by dotted line 18 forming the base of the casing, and the material surrounding the same forming the side and peripheral walls 50 thereof. A circular aperture 20 and an elong-

gated aperture 22 are formed in the base portion 18 and a tab 24 is struck up therefrom, for a purpose to be described hereinafter. A slot 26 is also provided to receive lug 28 of base plate 16 when the device is being 55 assembled.

Bosses 30, and a raised or embossed area 32 in each side wall are formed by the dies as the blank is pressed into shape. The portions 34 beyond the outer extremities of apertures 20 and 22 are deformed into vertical planes as clearly indicated in Fig. 2.

The outer margins of the blank are curved together as at 36 above portions 34 and over the top of the casing into abutment at 38 to 65 form a complete enclosure except for the apertures in the base 18. One or both of the side walls of the casing have a projecting portion 40 extending from the transverse central plane of the casing forwardly through 70 a suitable aperture in base plate 16, and terminating in lugs 42 adapted to be turned over or otherwise deformed to lock the casing in place in the base plate. Where both tabs or lugs 42 are carried by one side wall and 75 bent in opposite direction to clinch plate 16 in place, the twisting tendencies of the lugs when force is exerted to pull plate 16 away from the casing, are exerted in opposite senses on portion 40 and therefore neutralize each 80 other.

Plate 16 is preferably a driving fit on the casing, and the parts are assembled by inserting lug 28 in slot 26 and then forcing the casing into the position shown in Figure 2 85 by rotation around the lug. Lugs 42 are bent over and, if desired, spot welded to plate 16, and the assembly is complete.

The edges of apertures 20 and 22 are carefully rounded or beaded as clearly shown 90 in Fig. 2 to guide the cord with a minimum of friction and wear. No "mouse" is required to insert the cord, which should be entered through aperture 20, passing up and over the pulley and out at aperture 22. In 95 passing around the pulley, the cord acquires a certain degree of curvature, and if the base 18 were flat near aperture 22, the cord might follow the pulley past the aperture. Lug 24 is bent up to form a baffle completely 100

preventing any such contingency, and aperture 22 is elongated toward the transverse central plane of the casing. On account of this elongation the cord will in many instances pass out through aperture 22 without any assistance, but if it should tend to follow the pulley, baffle 24 will effectually deflect it through the aperture.

The pulley I employ comprises duplicate stampings 44 assembled on a sleeve 46 supported by pintle 10, and apertured for the reception of annular sheet metal riveting devices 48.

Without further elaboration, the foregoing will so fully explain the gist of my invention, that others may, by applying current knowledge readily adapt the same for use under various conditions of service, without eliminating certain features which may properly be said to constitute the essential items of novelty involved, which items are intended to be defined and secured to me by the following claims.

I claim:

25. 1. In a device of the class described, a sheet metal casing formed of a single piece of material, and a face plate apertured to be a driving fit on the outside of said casing.
2. In a device of the class described, a sheet metal casing formed of a single piece of material, comprising a base portion, and side walls curved inwardly along their edges into abutment to form the end and top walls of the casing, said base portion being apertured for passage of a cord twice through the same.
35. 3. In a device of the class described, a sheet metal casing formed of a single piece of material, comprising a base portion, and side walls curved inwardly along their edges into abutment to form the end and top walls of the casing, and a face plate fitting tightly over said side walls to hold the abutting edges together and reinforce the casing, said base portion being apertured for passage of a cord twice through the same.
45. 4. In a device of the class described, a one piece closed casing, a pulley within said casing, apertures in said casing for receiving a cord, said apertures completely encircling said cord only at points beyond where the cord leaves the pulley, one of said apertures being elongated.
55. 5. In a device of the class described, a one piece closed casing, a pulley within said casing, apertures in said casing for receiving a cord, said apertures encircling said cord only at points beyond where the cord leaves the pulley, one of said apertures being elongated, and a baffle adjacent said elongated aperture for directing the end of a cord thrust round the pulley through said aperture.
65. 6. In a device of the class described, a one piece closed casing, a pulley within said casing, apertures in said casing for receiving a cord, said apertures encircling said cord only

at points beyond where the cord leaves the pulley, one of said apertures being elongated, and a baffle struck up from said casing adjacent the edge of said elongated aperture to prevent the end of a cord from following the pulley groove past said aperture. 70

7. In a device of the class described, an apertured plate, a sheet metal casing having a closed side portion thereof entered laterally part way through said aperture and completely filling the same, and lug and slot means adjacent both ends of said aperture for holding the parts in assembled relation. 75

8. In a device of the class described, an apertured plate, a sheet metal casing having side walls entered through said aperture, and lug means projecting from one side wall only for penetrating said plate adjacent one end of said aperture and holding the parts in place. 80

9. In a device of the class described, a one-piece sheet metal casing having an integral edge, and the remaining edges closed by curving the side walls into abutment, a face plate lying perpendicular to the side walls and to the integral edge of said casing, said face plate being apertured and a driving fit on said casing, and said side walls being embossed to stiffen them over portions not engaged by said face plate. 85

10. In a device of the class described, a sheet metal casing formed of a single piece of material, comprising a base portion, side walls curved inwardly along their edges into abutment to close the end and top walls of the casing, said base portion being apertured for passage of a cord twice through the same, and a pulley in said casing, said casing closely housing said pulley throughout that portion of its periphery receiving the cord. 100

11. In a device of the class described, a casing comprising a flat topped base and sides integral with said base, and a pulley within said casing, said base being apertured for passage of a cord twice through the same. 110

12. In a device of the class described, a casing comprising a flat topped base and sides integral with said base, and a pulley within said casing, said base being apertured for passage of a cord twice through the same, said side walls terminating upwardly in arcuate portions conforming to the curvature of the top of the pulley. 115

In witness whereof, I hereunto subscribe my name this 31st day of December, 1921.

JOS. H. DILLON.
